UNITED STATES PATENT OFFICE.

JAMES SCULL, OF JERSEY CITY, NEW JERSEY, ASSIGNOR OF ONE-HALF TO
SAMUEL VANCE, OF SAME PLACE.

MANUFACTURE OF GREEN-SAND CORES.

SPECIFICATION forming part of Letters Patent No. 296,880, dated April 15, 1884.

Application filed March 6, 1884. (No model.)

To all whom it may concern:

Be it known that I, JAMES SCULL, a citizen of the United States, residing at Jersey City, in the county of Hudson and State of New Jersey, have invented certain new and useful Improvements in the Manufacture of Green-Sand Cores, of which the following is a specification.

My invention has for its object to form solid, hard, and durable sand cores for casting, and to effect the construction thereof with rapidity; and my invention consists in the mode described hereinafter of packing the green sand with great force upon a revolving mandrel so firmly as to secure a core of the desired hardness and durability.

In the drawings, Figure 1 is a sectional elevation of a machine by which the cores are manufactured. Fig. 2 is a plan view, the hopper removed.

The solid or hollow and perforated mandrel F turns in suitable bearings above a sand-box, J, and is revolved by means of a handle, a, opposite the end of a flat tube, E, equal in width to the length of the mandrel, and extending from a wind-box, C, into which a blast of air is forced through a tube, L, by means of the fan M or other suitable blowing apparatus. Above the tube or wind-box is a hopper, D, which communicates with the tube through a narrow opening, x, at the bottom, regulated by a slide or valve, n, and above the hopper revolves a riddle, G, into which the green sand is put, and through which it is sifted into the hopper. The sand falls from the hopper in a regular thin stream, and as it enters the tube E is struck by the rapid current of air forced forward by the blower, and is carried with great force against the sides of the mandrel, and densely packed thereon as the same is revolved, a knife, A, trimming down excrescences until the core is of the proper size.

I am aware that cores have been formed by dropping the sand upon a revolving mandrel; but this means of projecting the sand does not pack it upon the mandrel with sufficient density to form a core as hard and durable as is

required for many purposes; but an air-blast projects the sand with such force upon the 50 mandrel as to form a hard solid coating, better capable of withstanding the pressure of the molten metal than a core built up by hand in the usual manner.

The use of the riddle G prevents the introduction into the tube E of large pieces which might obstruct the tube and interfere with the formation of the core, and also separates the particles, so that they are carried by the air-blast without contact with the tube, and thereby prevented from adhering thereto. The riddle is revolved from a shaft, d, by means of a belt and pulleys, and a hammer, H, is vibrated to strike the riddle at regular intervals, so as to loosen the sand from the sieves, 65 preventing the latter from becoming clogged up.

To regulate the force of the air-current the box C is provided with an opening covered by a slide, p, which may be moved to a greater 70 or less extent, to permit the escape of a portion of the air, and thereby reduce the pressure in the box.

It will be obvious that the air-passage may be supplied with sand by feeding it in any 75 other manner than that described that will secure the introduction of small quantities across the whole width of the passage in a regular manner.

I do not here claim the devices herein set forth 80 for carrying out my process, as these form the subject of a separate application for Letters Patent, No. 121,529, filed February 21, 1884.

I claim—

The improvement in making cores herein 85 set forth, the same consisting in forcing the green sand by an air-blast upon a revolving mandrel, to pack the same thereon, as specified.

In testimony whereof I have signed my name 90 to this specification in the presence of two subscribing witnesses.

JAMES SCULL.
